UNITED STATES PATENT OFFICE.

SAMUEL PUTRA, OF LANSFORD, PENNSYLVANIA.

COBBLER'S PLIERS.

1,320,915.

Specification of Letters Patent.

Patented Nov. 4, 1919.

Application filed March 20, 1917. Serial No. 156,075.

To all whom it may concern:

Be it known that I, SAMUEL PUTRA, a citizen of the United States, residing at Lansford, in the county of Carbon, State of Pennsylvania, have invented certain new and useful Improvements in Cobblers' Pliers; and I do hereby declare the following to be a full, clear, and exact description of the invention, such as will enable others skilled in the art 10 to which it appertains to make and use the same.

This invention is an improvement in tools and has particular reference to a cobbler's pliers.

15 An object of the invention is to facilitate the removal of the layers or lifts of leather comprising the heel of the shoe when repairing the same and, to this end, use is made of a pair of coöperating jaw members of improved construction, one of which is provided with teeth or serrations adapted to engage the outer surface of the bottom layer or lift of a heel and tightly grip the same to prevent slipping of the tool, while the 25 other jaw has a point or projection for insertion between the bottom and next adjacent lift or layer whereby the same may be removed.

Another object is the provision of a device 30 of this character which is simple in construction, easy to manufacture and effective in carrying out the purpose for which it is designed.

The inventive idea involved is capable of 35 receiving a variety of mechanical expressions, one of which, for the purpose of illustrating the invention, is shown in the accompanying drawing, wherein:—

Figure 1 is a perspective view of the tool 40 showing the application thereof.

Fig. 2 is a side elevation of the tool.

Fig. 3 is an end elevation.

Referring more particularly to the accompanying drawing in which like reference 45 characters indicate similar parts the numerals 5 and 6 indicate the handle portions of the tool which may be of any preferred construction and which are pivoted in the usual manner as at 7.

50 The jaw members 8 and 9 formed upon adjacent ends of the handle portions 5 and

6 respectively embody the essential features of the invention and are shown in what is now believed to be their preferred forms wherein the jaw 8 is flattened as indicated at 55 10 and from this flattened portion the inner and outer faces of said jaw converge or taper toward the free end thereof. Likewise, the opposite edges of said jaw also taper or converge toward the free end thereof and the 60 extremity of said jaw is notched as indicated at 11 to form the teeth or serrations 12 which are adapted to bite into the lifts or layers of the heel of the shoe in order to prevent the tool from slipping and also provide a fulcrum about which the tool is turned in order to remove said lift or layer.

The opposed jaw 9 also has its inner and outer faces and opposite edges tapered and converging toward the free end thereof similar to the faces and edges of the jaw 8, but the free extremity of said jaw 9 terminates in a sharp projection or point 13 which, when the extremities of said jaw are in engagement, will engage between the teeth or 75 serrations 12 and in the notch 11.

In practice, when removing a lift from the heel of a shoe the teeth 12 of the jaw 8 are first engaged with the bottom of said lift after which the handle 6 of the jaw 9 is operated to cause the point or projection 13 of said jaw to engage between the bottom and next adjacent lifts and by further compressing said handles the point 13 will enter between the layers and owing to the tapered 85 construction of the jaw 9 the entrance of said point will be facilitated. The tool is then laterally rocked upon the extremity of the jaw 8 and as the lift loosens, the tool is swung backwardly so that its bearing surface will progress toward the base of the 90 jaw 8, the lateral rocking being continued, when it is found that the lift is readily removed.

What is claimed is:—

A pair of cobblers' pliers for removing heel lifts having a pair of jaws one of which has its side faces and its inner and outer faces converged to a point to enter beneath the heel lift and the other jaw of 100 which has inner and outer faces converged to an edge that is notched with resultant

pointed teeth between which the point of the first named jaw is adapted to fit, the side faces of the second jaw being converged to said notched edge whereby said notched edge is of short length to permit of rocking manipulation thereof upon the outer face of the lift to be removed.

In testimony whereof, I affix my signature in the presence of two witnesses.

SAMUEL PUTRA.
